UNITED STATES PATENT OFFICE.

JAMES A. MONTGOMERY, OF LOS ANGELES, CALIFORNIA.

DESIGN FOR A BADGE.

No. 38,469.

Specification for Design.

Patented March 5, 1907.

Application filed January 18, 1907. Serial No. 352,965. Term of patent 14 years.

To all whom it may concern:

Be it known that I, JAMES A. MONTGOMERY, a citizen of the United States, residing at Los Angeles, in the county of Los Angeles and State of California, have invented a new, original, and ornamental Design for Badges, of which the following is a specification, reference being had to the accompanying drawing, forming part thereof.

The figure is a plan view of a badge, showing my new design.

I claim—

The ornamental design for a badge as shown.

JAMES A. MONTGOMERY.
